UNITED STATES PATENT OFFICE.

FRANK APPLEBY AND EDWIN A. HUBBART, OF WATTS FLATS, NEW YORK.

BAG-HOLDER.

1,018,228.

Specification of Letters Patent. Patented Feb. 20, 1912.

Application filed May 13, 1911. Serial No. 626,906.

To all whom it may concern:

Be it known that we, FRANK APPLEBY and EDWIN A. HUBBART, citizens of the United States, residing at Watts Flats, in the 5 county of Chautauqua and State of New York, have invented new and useful Improvements in Bag-Holders, of which the following is a specification.

The invention relates to bag holders, and 10 has for its primary object the provision of a holder of this character in which a bag may be conveniently held open for the easy filling thereof, the support for the bag being vertically adjustable, so as to permit 15 various sizes of bags to be supported thereby.

Another object of the invention is the provision of a bag holder in which the frame thereof may be readily and easily adjusted, so as to stand upon level or uneven 20 surfaces, without possibility of the tilting of the same.

A further object of the invention is the provision of a bag holder which is simple in construction, durable, reliable and efficient in operation, and inexpensive in manufacture.

With these and other objects in view, the invention consists in the construction, combination and arrangement of parts, as will 30 be hereinafter more fully described, illustrated in the accompanying drawings, and pointed out in the claim hereunto appended.

In the drawings: Figure 1 is a perspective view of a bag holder constructed in 35 accordance with the invention, the same showing a bag supported thereby. Fig. 2 is a vertical longitudinal sectional view through the bag holder. Fig. 3 is a sectional view on the line 3—3 of Fig. 2. Fig. 40 4 is a sectional view on the line 4—4 of Fig. 2.

Similar reference characters indicate corresponding parts throughout the several views of the drawings.

45 Referring to the drawings by numerals, the bag holder comprises a frame, the same including front and rear supporting legs 5 and 6, respectively, the lower ends of which are slightly outbent, so as to be spread 50 apart a considerable distance from each other, and are formed with outturned feet 7, provided with suitable perforations through which are passed fasteners for the securing of the frame in upright position 55 upon a foundation, the upper ends of the

legs 5 being rearwardly and inwardly curved and engaged in a T connection 8, while the upper end of the rear leg 6 is also engaged in said connection, so as to give rigidity and strength to the frame.

Connected medially with the front and rear legs 5 and 6 is a rearwardly arched brace iron 9, the ends of which are bent to form eye clips 10 which embrace the front legs 5 and have passed therethrough bolt 60 members 11, thus securing the said clip ends 10 fast about the front legs. Embracing the rear leg 6 and fastened in the brace iron 9 is a staple-like fastener 12 which secures the brace iron to the rear leg of the frame. 70 Thus, it will be obvious that the brace iron will prevent the outward spreading of the legs when subjected to strain, or a heavy weight.

Connected with the frame for vertical adjustment thereon is a hopper supporting bracket, comprising front and rear sections 13 and 14, respectively, the same being formed with alining notches in their inner 75 adjacent edges for receiving the front legs 80 5 of the frame.

Formed medially in the front edge of the front section 13 of the bracket is a semi-circular recess, in which is seated a funnel-like hopper 15, the latter being secured to 85 the bracket by means of suitable fasteners 16, and secured to the flared mouth edge of this hopper 15 are strap yokes 17, the same loosely embracing the front legs 5, so that the hopper will be sustained rigid and prevented from displacement on the latter when 90 the same has been adjusted vertically upon the frame.

Secured in the front section 13 of the bracket and passed through a suitable opening in the rear section is a binding screw 18, on the outer end of which is threaded a winged nut 19, the latter working against the rear or outer edge of the section 14, so that upon working the nut inwardly upon 95 the screw 18, the sections 13 and 14 of the bracket will be clamped to the front legs 5 of the frame, thereby sustaining the said bracket in adjusted position on the latter. The front section 13 of the bracket has 100 mounted therein dowel pins 20, projecting rearwardly from its rear edge and engaged in suitable sockets formed in the rear section 14 for guiding the latter toward and away 105 from the front section, and also serving to 110

prevent any correlative movement of the sections of the bracket when being adjusted on the frame.

Mounted exteriorly at intervals upon the 5 hopper 15, near its lower edge, are hooks 21, with which is engaged and hung a bag 22 for sustaining the same open, and holding it in proper position while being filled.

The hopper may be lowered or elevated 10 from the foundation on which stands the frame, so as to accommodate bags of varying lengths when hung on the hooks on the hopper for the filling of said bag.

It is evident that the bracket may be 15 locked in adjusted position, when vertically adjusted on the frame.

What is claimed is:

A bag holder comprising a supporting frame having downwardly diverging front 20 and rear legs, a coupling connecting the up-

per ends of the legs together, a rearwardly arched brace iron engaged with each of the legs intermediate the ends thereof, an adjustable bracket carried by the frame, means for clamping said bracket to the frame, a 25 hopper fixed to the bracket and having guide links at its mouth edge embracing the front legs of the frame, and hooks fixed to the hopper at intervals thereon near its lower edge for the hanging of a bag upon 30 the hopper to sustain the said bag in open position.

In testimony whereof we affix our signatures in presence of two witnesses.

FRANK APPLEBY.
EDWIN A. HUBBART.
